BILTON B. GOINGS,
Inventor

By *Clarence O'Brien*,
Attorney

UNITED STATES PATENT OFFICE

BILTON B. GOINGS, OF EXPORT, PENNSYLVANIA

TABLE OR SHELF FOR A STOVE

Application filed September 20, 1932. Serial No. 634,069.

This invention relates to a table or shelf for a stove, the general object of the invention being to provide a table or shelf for a stove which can be easily attached to the stove or removed therefrom, and which can be used for supporting articles adjacent the stove, thus eliminating one having to walk back and forth from the stove to a cupboard or the like with pots, pans, and the like.

10 This invention also consists in certain other features of construction and in the combination and arrangement of the several parts to be hereinafter fully described, illustrated in the accompanying drawing and specifically 15 pointed out in the appended claim.

In describing the invention in detail, reference will be had to the accompanying drawing wherein like characters denote like or corresponding parts throughout the several 20 views, and in which:—

Figure 1 is an upper perspective view showing the invention in use on a stove.

Fig. 2 is a lower perspective view.

Fig. 3 is a top plan view of the table or 25 shelf.

Fig. 4 is a bottom plan view thereof.

Fig. 5 is a section on line 5—5 of Fig. 3.

Fig. 6 is a view of the brace supports.

In the drawing, the numeral 1 indicates 30 the table or shelf having its corners rounded, and its edges grooved to provide the rib 8 on the upper face which not only acts to strengthen the table or shelf but also prevents articles from sliding or falling there- 35 from. One side of the table is formed with the extension members 9 having hooks 10 at their free ends for engaging portions of the top of the stove as shown in Figs. 1 and 5 with a side edge of the table or shelf engag- 40 ing a part of a side edge of the top part of the stove, as also shown in Figs. 1, 2 and 5.

A pair of brace supports 2, preferably made 45 of steel wire, supports the compression from a load placed on the table or shelf, the tension being taken care of by the members 9. The brace supports 2 are connected together by the clamp rod 3 and one limb of each member 2 is substantially straight and extends up- 50 wardly and outwardly from the bight part 4 and the other or upper limb is bowed down-

wardly as shown. The extremity of each limb is bent into substantially hook-shape to engage any desired perforation of a row of perforations formed in an angle bar 6, a pair of which is suitably connected to the under face of the table or shelf, such as by rivets 7. Of course the bars 6 can be fastened to the table in any other suitable manner.

The bight parts of the two members 2 have the tubular members 4 thereon which are 60 formed of rubber or the like and pressed against the side of the stove, as shown in Figs. 1, 2 and 5, to prevent the brace members from marring the stove.

It will of course be understood that the 65 device can be used on any kind of a stove, such as coal, gas and electric stoves, and it will also be seen that the device can be easily and quickly placed on the stove or removed therefrom and that the device can be manufactured to sell at low cost. The brace mem- 70 bers can be adjusted to suit the stove on which the device is placed, due to their detachable connection to the perforated bars 6, and the device will save a housewife or cook a great 75 deal of work as it eliminates walking back and forth from the stove to a cupboard or the like and carrying pots and pans from the stove to the cupboard or from the cupboard to the stove, as the articles can be placed on 80 the table.

It is thought from the foregoing descrip- 85 tion that the advantages and novel features of the invention will be readily apparent.

It is to be understood that changes may 90 be made in the construction and in the combination and arrangement of the several parts, provided that such changes fall within the scope of the appended claim.

Having thus described my invention, what 90 I claim as new is:—

An attachment for a stove comprising a 95 table, hook members connected to one side of the table and having their hook portions engaging parts of the stove, a pair of strips connected with the under side of the table and each having a depending part provided with a longitudinally extending row of holes, a pair of brace members, each of substan- 100 tially U-shape, and having a substantially

straight vertically arranged bight and the limbs extending upwardly and outwardly from the bight with one limb longer than the other and both limbs having their free ends
5 bent to engage certain holes in the strips, the bight portions resting against a side of the stove and a bar having bent ends engaging the lower limbs of the U-shaped members for holding said members together in spaced
10 relation.

In testimony whereof I affix my signature.
BILTON B. GOINGS.
